UNITED STATES PATENT OFFICE.

ANDREW J. BROOKINS, OF CHICAGO, ILLINOIS.

AUTOMATIC TRAIN CONTROL.

Application filed May 22, 1922. Serial No. 562,594.

To all whom it may concern:

Be it known that I, ANDREW J. BROOKINS, a citizen of the United States, and a resident of Chicago, in the county of Cook and State 5 of Illinois, have invented certain new and useful Improvements in Automatic Train Control, of which the following is a specification, reference being had to the drawings accompanying and forming a part hereof.

10 This invention relates to train control apparatus which is actuated intermittently by mechanical and electrical contact with track side installations positioned at definite points along the trackway; the indications 15 of said actuation being retained between adjacent track side installations, and being made at each of said installations, whether said making repeats the last previous indication or changes the same.

20 Among the objects of this invention are, to obtain a car carried installation comprising the hereinafter described apparatus, signals and electrical conductors, by means of which all the essential indications required 25 are obtained upon the co-action therewith of track side installations whereof a ramp consisting of an ascending and a descending section is an element; said descending section being insulated and arranged to re-

30 main de-energized or to be energized by an electrical current flowing therethrough in a selectively determined direction to correspond with the condition of pre-determined sections of the track way, on the contact therewith of a co-acting member of said car 35 carried installation; to obtain a car carried apparatus which can easily be made inoperative when the engine or motor which is equipped therewith is to be used for yard work, or for pushing on road work, to obtain means to direct air from the train pipe to register a plurality of audible signals; and to obtain a car carried apparatus where- 40 of the member thereof which is adapted to co-act with a descending section of a ramp will be forced into close contact therewith, particularly at the time of its initial contact; and to obtain an apparatus of the kind de- 45 scribed which is simple in construction, ef- fective in operation, not liable to be broken or get out of order, and easily understood.

50 In the drawings referred to Fig. 1 is a diagram of track and track side installations adapted to co-act with car carried apparatus embodying this invention,

Fig. 2 is a diagram of track and track side elements and of elements in said car carried apparatus, forming at pre-determined definite points an electric circuit.

Fig. 3 indicates the electro and permanent 60 magnets entering into the construction embodying the invention.

Fig. 4 is an enlarged vertical section of the mechanical locking member and associated parts forming elements of the construction illustrated and hereinafter described.

Fig. 5 is a top plan view of the lower part of the shell of the apparatus, showing the operable parts thereof.

Fig. 6 is a vertical section of the housing, showing in elevation a shoe and a vertically movable plunger and the associated parts, of an apparatus embodying features of the invention; said plunger illustrated in "clear" 75 position.

Fig. 7 is a horizontal section, on line 7—7 of Fig. 6, viewed as indicated by arrows; showing operable parts in top plan view.

Fig. 8 is a vertical section of the shell of 80 the apparatus, and of the plunger and associated parts, viewed at an angle of ninety degrees from the view thereof illustrated in Fig. 6.

Fig. 9 is a vertical section of the plunger 85 chamber, showing a portion of the plunger in elevation, in "caution" position.

Fig. 10 is a similar view of the several members illustrated in Fig. 9, with said plunger in "danger" position.

A reference character applied to designate a given part indicates said part throughout the several figures of the drawings wherever the same appears.

In Fig. 1 a plurality of blocks of railway 95 track are diagramed, said blocks being numbered 1, 2, 3 and 4, and each block is provided with similar installations, the characters designating a member or element being provided with an index letter or numeral indicating the block in which it is situated.

A^1, A^2, A^3, A^4 , and B^1, B^2, B^3, B^4 , represent rails in blocks 1, 2, 3, and 4, respectively. C, C, C , represent insulating material separating the rails of one block from those of an adjacent block. X^1, X^2, X^3 , represent batteries in blocks 1, 2, 3, respectively: Y^1, Y^2, Y^3, Y^4, Y^5 , represent track-side relays, and A^Y, B^Y , and A^X, B^X , respec-

tively represent conductors from rails A, B, to electromagnets of the Y series and batteries of the X series in the several blocks. The track side installations in said Fig. 1, 5 comprise the ramp rails D¹, D², D³, of blocks 1, 2, 3, each of said ramps consisting of an ascending section (d), and a descending section (d¹). Said track side installations also include batteries Z², Z³, Z⁴, movable conductors E², e², F², f², E³, e³, F³, f³, E⁴, e⁴, F⁴, f⁴, the conductors G², g², G³, g³, G⁴, g⁴, H², h², H³, h³, H⁴, h⁴, contact points I², i², I³, i³, I⁴, i⁴, J², j², K², k², J³, j³, K³, k³, J⁴, j⁴, K⁴, k⁴, and conductors L¹, l¹, L², l², L³, l³.

10 It is to be understood that the movable conductors F², f², F³, f³, F⁴, f⁴, are armatures to relays, y², y³, and y⁴, and are controlled thereby, forming pole changers of the track side installations of which they are, respectively, elements; and further, that none of the installations or constructions illustrated in Fig. 1, (other than the ramps of the D series), form elements of this invention, said elements being diagrammed and described to 15 illustrate the manner in which the track and track side installations co-act with the apparatus embodying the invention.

Omitting recital of the index numeral which designates the block in which they are positioned, the L conductors electrically connect a descending section (d¹) of a ramp of a given block and contact points (J, k), of the adjacent block; and the l conductors electrically connect a rail (A) with contact points j, K, of the adjacent block. The G, g, conductors electrically connect a battery (Z) to a movable conductor (e, E,) of a given block, and the H, h, conductors electrically connect a contact point (I, i), to a movable conductor, (F, f), of a given block.

20 M² represents a conductor extending from battery Z² to the coil of relay y², and m² a conductor from conductor H² to said coil of relay y². M³ represents a conductor extending from battery Z³ to the coil of relay y³, and m³ a conductor from conductor H³ to said coil of relay y³.

25 W¹, W⁴, respectively represent a car or engine on blocks 1 and 4.

30 In Fig. 2 a completed electric circuit is diagrammed and lettered to correspond with Fig. 1, so far as the track side installation is shown, but without the index numerals indicating blocks; and lettered to correspond with the cab carried elements as hereinafter described.

35 From the foregoing descriptions of Figs. 1 and 2 it is evident that if the movable conductors E², e², and pole changers F², f², are in the position indicated in block 2, Fig. 1, a partial electric circuit is formed, which, when completed by the shoe (N) of the car carried apparatus, hereinafter described, coming in contact with ramp D, (as indicated in Fig. 2) is energized by battery Z

40 and the current will flow in a pre-determined direction; and if said pole changers F², f², are in the position of pole changers F³, f³, as indicated in Fig. 1, (in block 3), upon the completion of the circuit in the manner described, said current will flow in the opposite direction.

45 Referring to Figs. 2 and 6, N represents a shoe carried by the car carried apparatus, S an electromagnet, n a conductor from shoe N to electromagnet S, O a car or truck wheel, and n¹ a conductor from electromagnet S to said wheel O.

50 Shoe N is illustrated in Fig. 6 as pivotally mounted on the housing (P) of the apparatus, by means of levers or links N¹, N¹. Housing P is attached to the truck of a locomotive tender, or cab. p (Fig 8) represents the upper part, or cover, of housing P. P¹, (Fig. 8), represents the walls of cylindrical chamber p¹, and P², p², plungers which are longitudinally movable in said chamber. The walls of chamber p¹ are represented as integral with housing P. p³ represents an inlet to chamber p¹, and the receiving end of said inlet is in communication with the train pipe of the air brake system of the train. P³, p⁴, respectively represent outlets from chamber p¹. In Fig. 6 outlet P³ is illustrated as in communication with the bell actuating device W¹, by way of pipe or conduit W²; and the outlet p⁴ as in communication with signal W⁴, by means of pipe or conduit W³. W⁵ represents a bell, sounding whereof is controlled by actuating device W¹. P⁴ represents a manually operable valve, the movable plug whereof is provided with the passage way p⁵. Valve P⁴ is illustrated in Fig. 7 with said passage way p⁵ in axial line with passage way p⁴, and is indicated by broken lines in said figure in position so that said plug does not obstruct said passage way.

55 P⁵, p⁶, respectively represent air retaining piston cups on plunger P², said cups being separated by ring P⁶, and held rigidly in place by nut p⁷. P⁷, P⁷, respectively represent glands or stuffing boxes to plungers P², p², to prevent the flow of air from chamber p¹, while permitting said plungers to move longitudinally. Plunger P² is provided with a longitudinally extending cylindrical chamber, p⁸, in which the piston P⁸ is placed, and is longitudinally movable. P⁹, p⁹, represent laterally extending passage ways which communicate with chambers p¹ and p⁸, forming inlets to said chamber p⁸. P¹⁰ represents an air retaining cup on the upper end of piston P⁸, which is arranged to obstruct the lower one of said passage ways (p⁹) when piston P⁸ is held in normal position and "clear" is indicated, as is illustrated in Fig. 8. p¹⁰ represents a shoulder at the lower end of chamber p¹ and P¹¹ an annular flange on piston p², which is adapt-

130

ed to engage said shoulder and prevent said piston, (p^2) being forced out of chamber p^1 in case of removal or breaking of shoe N.

Q, Fig. 6, represents a lever which is mounted on shaft q . Q^1 represents a head or flattened end of shaft q , positioned in recess q^1 , on the end of the plug of valve P^4 , (see Fig. 7). q^2 represents a slot in lever Q, and Q^2 a bolt in said slot. Bolt Q^2 is secured in arm Q^3 , which is mounted on plunger P^2 , to make a rigid joining, (Fig. 8). By this arrangement the upward movement of the plunger turns lever Q and shaft q , and in case the plug of valve P^4 is manually turned to obstruct passage way p^4 , said shaft (q) turns said plug to make said passage way continuous.

The arm Q^3 is provided with recesses or notches q^3, q^4 , which are well represented in Fig. 6. Q^4 represents a shoulder on the upper end of plunger P^2 , which is formed by the head of arm Q^3 being of greater diameter than said plunger. R, r , respectively represent pawls which are pivotally mounted on pins R^1, r^1 , and R^2, r^2 , represent links which are pivotally connected to said pawls, respectively. R^3 represents a permanent magnet, which is rigidly mounted on frame r^3 , and said frame is pivotally mounted on pin or bolt R^4 . R^5 represents a standard on frame r^3 . One end of each of the links R^2, r^2 , is attached to standard R^5 by pivot or pin r^4 . By this arrangement the swinging of frame r^3 , on pivot R^4 , moves pawls R, r , on their respective pivots R^1, r^1 , so that the engageable ends of said pawls, one or the other thereof, is in the path of movement of the head of arm Q^3 , and engageable in the recesses q^3, q^4 , one or the other thereof, depending on whether said movements of said pawls is to the left or to the right, as viewed in Fig. 6. The frame r^3 is pivoted on frame S^2 , by the recited pin or pivot R^4 (see Fig. 6).

S, Figs. 2, 3, 5 and 6, represents an electromagnet, S^1 the pole piece thereof, and S^2 the frame on which the electromagnet (and frame r^3) are mounted.

R^3 being a permanent magnet and mounted to form a polarized armature to electromagnet S, the flow of electric energy in one direction through the coil of said magnet, magnetizes said pole piece to attract one and to repel the other of the ends of said armature, turning said armature and frame (r^3) on pivot R^4 , say into the position illustrated in full lines in Fig. 6, and when said flow is in the opposite direction it oppositely magnetizes said pole piece, to attract and repel said magnet oppositely, moving it and frame r^3 in the opposite direction. The turning of frame r^3 as recited, turns pawls R, r , on their pivots R^1, r^1 as described.

The movement of arm Q^3 in an upward

direction, (by the upward movement of plunger P^2 when shoe N contacts with the ascending section of a ramp (D)), forces pawls R, r , back, (on their pivots) into a neutral position, that is, into a position where neither of said pawls is in the path of movement of arm Q^3 , to be engageable with the recesses q^3, q^4 , and said forcing of said pawls into said neutral position turns frame r^3 on its pivot R^4 , so that the permanent magnet, or polarized armature, R^3 , is in neutral position; and to retain said polarized armature in said neutral position, so long as the electromagnet S is not energized, I provide the neutral armature T, pivotally mounted on t , and having projection or nose T^1 , which is adapted to engage with recess t^1 , in frame r^3 , (see Fig. 4). When electromagnet S is not energized, armature T will turn, by gravity, on its pivot t , so that end or nose T^1 is in recess t^1 , thereby locking and holding said frame and magnet R^3 , together with pawls R, r , locked in neutral position. The foregoing is to prevent the jarring of said pawls R, r , into engageable position with the recesses in arm Q^3 , when "danger" signal is required, (no current flowing at said time in either direction through the coils of electromagnet S).

When electromagnet S is not energized the pole piece S^1 thereof is an armature which is attracted by either pole or end of magnet R^3 , and it follows that said permanent magnet having been attracted and turned, together with frame r^3 , on pivot R^4 , to a given position, as before recited, said pole S^1 tends to hold said permanent magnet in said position, until said permanent magnet is mechanically forced into neutral position by plunger P^2 , as described. It also occurs that in case of movement of the permanent magnet in a given direction, initiated by the energizing of the electromagnet S, said movement will be continued by the mutual attraction of said pole piece S^1 and the end of the permanent magnet which is nearest thereto, without regard to the continuity of said energizing of the electromagnet.

The last recited action between the pole piece S^1 and the ends or poles of the permanent magnet produces certainty of proper operation of the apparatus, in case of an intermittent electric contact of the shoe N on the descending side of a ramp.

To enable the engineer or other person in charge thereof to put the apparatus in inoperable condition, when on an engine or tender, the hub of arm Q^3 , previously referred to as of greater diameter than is the portion of plunger P^2 which is adjacent thereto, the member U is mounted on pivot u , so that by pulling bolt U^1 said member U may be forced against the plunger and, said plunger being manually raised, said

member may be forced underneath said shoulder, or flange (Q⁴). When the plunger P² is thus secured in said raised position the cup p⁶ is above the outlet P³, and chamber p¹ is sealed.

With the plunger in the last described position the engine may be used in the yard and on the road precisely as if the apparatus were not attached thereon, it being elevated so high that the shoe N in going over a ramp will not raise or otherwise affect said plunger, or the apparatus.

When two or more engines are coupled together, or one is to be used as a pusher, or for yard work, and it is desired to cut the apparatus out of service, the plunger P² is moved upward, as recited, and locked in said position, (indicated by broken lines in Fig. 6). The pawl U being moved into position underneath shoulder Q⁴, the hub of arm Q³ rests on said pawl. And while in this position cup p⁶ cuts off, or obstructs, communication from inlet p³ and outlets P³, p⁴, and the cup P¹⁰ on piston p⁸ registers below the lower one of outlets or passage ways p⁹; but this position of said cup P¹⁰ is immaterial, because of said obstruction by cup p⁶ between the inlet p³ and outlets p³, p⁴.

When the apparatus is in operable condition and the plunger P² is in its normal or "clear" position, the shoe N will engage the ascending section, (d) of a ramp and raise plunger p², before said last named plunger engages plunger P² to raise it. This arrangement is designed to prevent excessive shocks between the apparatus and the ramp rail. The upward movement of the plunger moves arm Q³ upward and turns lever Q and shaft q, by means of bolt Q² in recess q², and said upward movement of arm Q³, (see Fig. 6), mechanically forces pawls R, r, back to neutral positions, and said movement of said pawls is transmitted, by links R², r², to frame r³, and polarized armature R³, (which is mounted on said frame), thereby turning said polarized armature to neutral position. The several last recited members are held in said neutral positions by nose or abutment T¹, of neutral armature T, falling, by gravity, into recess t¹ of frame r³, and there remaining so long as electromagnet S is not energized.

Upon continued upward movement of plunger P², the air retainer P⁵ passes inlet p³, allowing train line air to flow from said inlet into and through chamber p¹, (around spacing collar P⁶) and through conduit or outlet P³ and conduit W², to actuate the bell ringer W¹, and warn the engineer that a ramp (D) is being passed. At this time the air retainer or cup p⁶ prevents air flowing into the outlet p⁴.

In the last recited upward movement of the plunger as air retainer P⁵ passes the

inlet p³, air at train line pressure is trapped in chamber p¹, between said cup and gland P⁷ adjacent thereto, and said trapped air is compressed at the time shoe N is on the apex of the ramp, and as said shoe passes said apex said air under said pressure forces the plunger downward, with the added pressure of said compression to the train pipe pressure, ensuring good electrical contact between said shoe and said descending section, upon their initial contact.

Should said descending section of the ramp be energized the core S¹ of electromagnet S is energized, and the neutral armature T is attracted thereby, unlocking frame r³, by removing the nose T¹ of said armature from recess t¹, and at the same time the polarized armature R³ is moved to the right or to the left, correspondingly to the direction of the flow of electricity through the coil of said electromagnet; the pawls R, r, are correspondingly moved, and the arm Q³ of plunger P² is engaged by one or the other of said pawls entering the recess in said arm which is provided therefor; and the plunger is suspended in corresponding position.

When the indication transmitted is "clear" the direction of flow of current from the road side battery through the coil of the polarized electromagnet S will turn frame r³ and polarized armature R³, in a counter clockwise direction, as illustrated in Fig. 6. This pulls pawl R into engagement with notch q³ on arm Q³, thereby arresting the downward movement of the plunger. The retaining cup P⁵ is now in position to cut off communication between chamber p¹ and the outlets p³, p⁴, thereby preventing a flow of air from the train line.

When the indication transmitted is "caution" the direction of flow of current from the road side batteries through the coil of electromagnet S will turn the frame r³ and polarized armature R³ in a clockwise direction. This pulls pawl r into engagement with notch q⁴, thereby arresting the downward movement of the plunger. While the plunger is in this position the cup P⁵ is below outlet P³, thereby establishing communication between inlet p³ and said outlet, permitting train line air to flow into and actuate the bell ringer W¹, (by way of conduit W²), which gives a continuous caution indication until the next ramp is reached.

The quantity of air flowing from port P³ to actuate signal W¹, is not sufficient to bleed the train line through port p³, to cause an application of the brake.

When the indication transmitted is "danger" the circuit of the road side batteries, through the coils of electromagnet S is opened by the road side control apparatus,

The descending section of the ramp will not be energized, and the lock T^1 , t^1 , will remain in engagement, the armature and the pawls will therefore remain locked in neutral position as the shoe moves off the ramp, and the plunger will move to its downward limit of travel. The air retainer P^5 is now below outlet p^4 , thereby establishing communication between the train line and the atmosphere, through chamber p^1 , outlet p^4 and passage way W^3 , and audible signal W^4 , and said signal is sounded. It also causes an automatic application of the brakes, sufficient to bring the train to a stop.

15 After the train has been brought to a stop the engineer can, by dismounting from the cab, apply a wrench to and manually close the valve P^4 . This will prevent further escape of train line air to the atmosphere.

20 The train can then make a permissive movement through the "danger" block; but the caution signal is continuously sounding to give warning. When the next ramp is reached the valve P^4 is automatically opened, 25 on the upward movement of the plunger as the shoe ascends the ramp, by the flattened Q^1 engaging lugs q^1 , q^4 , (see Fig. 7). The valve will remain in this open position until it is again manually closed, as last 30 above described.

I claim;

1. In a train control apparatus, a cylindrical chamber provided with an inlet and with a plurality of outlets, in combination with a plurality of audible signals, and passage ways communicating with said outlets and said signals, a valve interposed in one of said passage ways, said valve manually operable to obstruct said passage way, and 40 a plunger longitudinally movable in said cylindrical chamber and arranged to obstruct said outlets and movable to selectively establish communication between said inlet and said outlets.

45 2. In a car carried apparatus, a cylindrical chamber provided with an inlet and with a plurality of outlets, in combination with a plunger, also provided with a cylindrical chamber, a longitudinally movable piston in said last chamber, means to retain said piston in said chamber, said retaining means comprising a member co-actuable with said plunger and a road side installation.

55 3. In a car carried apparatus, a cylindrical chamber provided with an inlet and with a plurality of outlets, in combination with a plunger also provided with a cylindrical chamber, a passage way communicating with said chambers, a longitudinally movable piston in said plunger chamber, means to retain said piston in said chamber, said retaining means comprising a member co-actuable with a road side installation to move said plunger in a determined direction, 60 an air retainer positioned on said piston ar-

ranged to control communication between said plunger and one of said outlets, and a road side installation.

4. In a car carried apparatus, a cylindrical chamber provided with an inlet and with outlets, a plunger longitudinally movable in said chamber, a plurality of air retainers mounted on said plunger in spaced relation, the upper one of said air retainers arranged to establish communication between said inlet and one of said outlets when said plunger is raised a determined distance, and simultaneously obstruct communication between said inlet and the other of said outlets, and when said plunger is raised an additional distance to obstruct communication between said inlet and both said outlets, and when said plunger is raised an additional distance, the lower one of said retainers arranged to obstruct communication between said inlet and both said outlets, and the upper one of said retainers arranged to trap air in said cylindrical chamber and apply additional pressure thereto on the continued raising of said plunger.

5. In a car carried apparatus, a cylindrical chamber provided with an inlet and with a plurality of outlets, a plunger longitudinally movable in said chamber, air retainers on said plunger in spaced relation, the upper one of said air retainers arranged to control the establishment of communication, on the downward movement of said plunger, between said inlet and both said outlets, and said retainers arranged to successively control the establishment of said communication, on the upward movement of said plunger, in combination with electroresponsive means to selectively arrest said plunger on said downward movement, and mechanically retain said plunger in said selected position.

6. In a car carried apparatus, a cylindrical chamber provided with an inlet and with a plurality of outlets, a plunger longitudinally movable in said chamber, means to lock said plunger in an inoperable position, in combination with a plurality of air retainers on said plunger arranged in spaced relation, the lower one of said retainers disposed to obstruct communication between the inlet and said outlets when said plunger is locked in said inoperable position, and the upper one arranged to trap air in said chamber when said plunger is in inoperable position.

7. In a car carried apparatus, an electromagnet, a polarized armature responsive to said magnet, said magnet arranged to be normally de-energized, a movable plunger, an arm rigidly mounted on said plunger and provided with a head provided with recesses, and pawls, in combination with a pivoted frame on which said polarized armature is mounted, and links joining said

pawls and said frame, said frame provided with a recess and said electromagnet provided with a neutral armature arranged to co-act with said recess, to lock said frame in a determined and neutral position when said magnet is de-energized, upon said head on said arm forcing said pawls and frame into inoperable and neutral position.

8. In a car carried apparatus, a pivotally mounted lever, a plunger, an arm rigidly mounted on said plunger, recesses in said arm, and a connection between said arm and said lever, in combination with movable pawls, links pivotally mounted on said pawls, a pivotally mounted frame, said links also pivotally joined to said frame, an electromagnet and a polarized armature to said magnet, said armature mounted on said frame, all arranged to control the position of said pawls by the electrical condition of said magnet.

9. In a car carried apparatus, a pivotally mounted lever, a plunger, an arm rigidly mounted on said plunger, a head on said arm and recesses on said head and a connection between said lever and said head, and a movably mounted frame, in combination with movably mounted pawls, links connecting said pawls and said frame, an electromagnet, and a polarized armature to said magnet mounted on said frame, all arranged to control the position of said pawls by the electrical condition of said magnet, said head forming mechanical means to move said pawls and polarized armature to neutral positions, means to lock said polarized armature in neutral position, and a neutral armature to said magnet, said neutral armature arranged to control said locking means.

10. A movably mounted arm having a head provided with recesses, on the free end thereof, a movably mounted plunger and a connection between said plunger and said arm, in combination with pawls arranged to be selectively engageable with said recesses, an electromagnet, a polarized armature to said magnet arranged to control said pawls, said free end of said arm arranged to mechanically force said pawls from said engagement, and electroresponsive means, arranged to co-act with said magnet, to lock said polarized armature in neutral position when said magnet is not energized.

11. In a train control system, road side members alongside of a track way at spaced intervals, a car carried apparatus comprising a chamber provided with an inlet and with an outlet, a plunger movably mounted in said chamber, an air retainer mounted on said plunger, means adapted to co-act with said road side members to move said plunger in a determined direction, and said plunger adapted to be manually additionally moved in said direction, in combination with man-

ually operable means to retain said plunger in said additionally moved position, said air retainer arranged to obstruct communication between said inlet and said outlets when said plunger is retained in said last named position.

12. In a train control system, road side members at spaced intervals along a track way, in combination with a car carried apparatus having a movable member, a plurality of locking members arranged to selectively co-act with said movable member, means arranged to co-act with said road side members to move said locking members in neutral position, an electromagnet, a neutral armature and a polarized armature, a connection between said polarized armature and said locking members, means to lock said polarized armature in a neutral position, and a connection between said neutral armature and said means to lock said polarized armature in said neutral position.

13. In a train control system, road side members installed at spaced intervals alongside a trackway, in combination with a car carried apparatus comprising a movable member, a plurality of locking members arranged to co-act with said movable member, means comprising said movable member arranged to co-act with said road side members to move said locking members into neutral position, an electromagnet, a movably mounted member controlled by said magnet, a connection between said movably mounted member and said locking members, and means controlled by said magnet to lock said movably mounted member in neutral position.

14. In a train control system, roadside members at spaced intervals along a track way, a car carried apparatus comprising a plunger, a member arranged to co-act with said roadside members to move said plunger in a determined direction, an arm rigidly mounted on said plunger, a plurality of locking members, said arm arranged to move said locking members to neutral position on said movement of said plunger, a movably mounted armature having permanent pole pieces of opposite polarity, a connection between said armature and said locking members, means to lock said armature in neutral position, and a neutral armature arranged to control said locking means, all combined as set forth.

15. In a train control system, roadside installations at spaced intervals along a trackway, in combination with a car carried apparatus comprising a chamber, a plurality of passage ways at spaced intervals in said chamber, one of said passage ways in communication with the air brake system of the train and the other of said passage ways communicating with signal

control devices, a plunger movably mounted in said chamber, a plurality of air retaining means on said plunger adapted to control communication between said passage ways and said chamber and to trap air in said chamber and simultaneously obstruct communication between said inlet and said outlet passage ways, and a plurality of locking members, and electroresponsive members arranged to co-act and to selectively arrest movement of said plunger in a determined direction.

16. In a train control apparatus, a movably mounted plunger, means whereby the position of said plunger controls the giving and selection of signal indications, in combination with a plurality of mechanical locks adapted to arrest said plunger in a selected position and magnetically controlled means to mechanically maintain said mechanical locks in inoperable position.

17. In a train control system, roadside members at spaced intervals along a track way, a movably mounted plunger, means whereby the position of said plunger controls the giving and selection of signal indications, in combination with a plurality of mechanical locks adapted to arrest said plunger in a selected position and to maintain said plunger in said selected position between road side members.

18. In a train control system, roadside members at spaced intervals along a track way, a movably mounted plunger, means whereby the position of said plunger controls the giving and selection of signal indications, electromechanical means to arrest said plunger in a selected position, said road side members arranged to co-act with said plunger to move said electromechanical means to an inoperative position and magnetically controlled means to mechanically maintain said electromechanical means in an inoperative position, all combined as set forth.

19. In a train control system, roadside members at spaced intervals along a track way, car carried apparatus comprising a movably mounted plunger, means whereby the position of said plunger controls the giving and selection of one of a plurality of signal indications, electromechanical means to arrest said plunger in a selected position, said road side members arranged to co-act

with said plunger to move said electromechanical means to inoperative positions, in combination with electroresponsive means to lock said electromechanical means in said inoperative positions.

20. In a train control system, a car carried apparatus comprising a chamber provided with an inlet and a plurality of outlet passage ways, a plunger movably mounted in said chamber, said plunger provided with air retaining means adapted to control communication between said passage ways, in combination with an electroresponsive device comprising a movably mounted member connected to a plurality of mechanical locks, said movably mounted member adapted to respond to the direction of flow of an electric current, and said mechanical locks arranged to selectively arrest movement of said plunger in one direction, and a road side member arranged to co-act with said plunger to mechanically move said locks to a neutral position and magnetically controlled means to mechanically lock said electromechanical means in said neutral position.

21. In a train control system, a movably mounted plunger, signal indications, means whereby the position of said plunger controls a signal indication, electromechanical means operable to arrest and maintain said plunger in a selected position, in combination with road side members at spaced intervals along a track way arranged to co-act with said plunger to move said electromechanical means to inoperative positions and magnetically controlled means to mechanically lock said electromechanical means in said inoperative position.

22. In a train control apparatus, an electromagnet in combination with a permanent magnet, one thereof movably mounted, magnetically responsive means to mechanically lock said movable magnet in a neutral position the pole of said electromagnet arranged to selectively attract and repel, by the direction of flow of electrical energy through the coil thereof, the poles of said permanent magnet, and said poles arranged, said coil being de-energized, so that the pole piece of said electromagnet is attracted by the pole of the permanent magnet which is nearest thereto.

ANDREW J. BROOKINS.
